UNITED STATES PATENT OFFICE

RICHARD J. GOLLONG AND RALPH H. CARTER, OF JOHNSON CITY, TENNESSEE, ASSIGNORS TO AMERICAN GLANZSTOFF CORPORATION, OF NEW YORK, N. Y., A CORPORATION OF DELAWARE

LOCKING DEVICE

Application filed September 12, 1931. Serial No. 562,592.

This invention relates to the treatment of threads in a washing or treating apparatus, and more particularly to an improved locking means for preventing any accidental movement of the feed and discharge pipes while the system is in operation. In describing the invention reference will be made to the use of the locking means in connection with an apparatus for treating artificial filaments, but it is not intended to limit the locking means to its use in the specific apparatus described.

In the treatment of artificial silk such as is disclosed in a co-pending application Serial Number 539,730, filed May 26, 1931, in the names of Oppenlaender, Gollong and Carter, filaments may be wound on perforated receivers which may be placed in tiers of three or more in a tank. Treating liquid is then allowed to flow into the tank and after the treating operation is emptied from the tank by vacuum or other suitable means.

It is an object of this invention to provide an improved locking means for preventing any accidental movement of the feeding and discharge pipes during the treating operation.

More particularly it is an object of this invention to provide a connection between the treating tank and the various feeding and discharge pipes which will prevent any movement of the connection until the treating tank is emptied.

In describing the invention reference will be made to the accompanying drawings in which:

Figure 1 is a side elevation of the improved apparatus;

Figure 2 is an end elevation of the apparatus shown in Figure 1; and

Figures 3 and 4 are detailed views showing the construction and arrangement of the float located in a compartment formed in the treating tank; and

Figure 5 is a detailed view of the locking means.

In the several drawings the numeral 10 designates a tank within which the thread is to be treated by liquids used in washing or treating the thread in the tank 10 of each

unit and conducted from separate storage tanks for these liquids through the filling lines 11a, 11b, and 11c, etc., having branches 12a, 12b, and 12c, etc., with shut off valves 13a, 13b, 13c, etc., said branches extending downwardly to provide outlets positioned on an arc of a circle described about a point above the pivot 14.

A pipe 15 is supported by the frame 16 which may be pivoted about the pin 14. The upper end of the pipe 15 is provided with a sleeve 17 having a flared upper end and adapted to telescope within the pipe 15. A handle 18, as illustrated more clearly in Figure 5, is pivotally mounted at 19 on the support 20, which is clamped to the pipe 15. The inner bifurcated ends of the handle 18 provide arms 21, 21 carrying inwardly extending pins upon which the rollers 21a, positioned between the flanges 22 and 23 fixed to the sleeve 17, rotate.

The lower end of the sleeve 17 carries a pin 24 about which the upper end of a rod 25 is bent to provide an elongated slot 26 within which the pin 24 will slide when the sleeve 17 is moved downwardly from its normal position. When the sleeve 17 is raised the pin 24 will engage the hook at the top of the rod 25 to lift the rod. The rod 25 passes through the pipe 15 and is provided with a hook 27 at its lower end that engages an eye in the valve 28 extending into and covering the outlet 29 of the T fitting at the lower end of the pipe 15. A pin 18a, which may be passed through one of the three holes 18b in the support 20 and a hole in the handle 18 which registers with one of said holes in its raised, lowered and normal position, serves to retain the handle and the sleeve 17 in the desired position.

The horizontally extending outlet 30 of the T fitting at the end of the pipe 15 communicates with the hole 31 in the bottom of the tank 10 through a pipe 32, a swivel connection positioned below the pivot 14, and a pipe 33.

Drain lines 34a, 34b, etc., lead the liquids discharged from the tank 10 to separate tanks for the liquids to be saved or reused or regenerated for reuse, and to the sewer for liquids to be discarded. These drain lines are

provided with receiving ports 35a, 35b, 35c, etc., which are positioned directly beneath the outlet of the pipe 15 and the line 36 when the pipe 15 is connected to filling lines 11a, 11b, 5 11c, etc., respectively.

The tank 10 is provided with a vertical baffle 37 extending across the tank from its top to within a short distance of its bottom. A horizontal baffle 38 is fixed to the baffle 37 10 near its lower end and extends over the inlet 31.

At one side of the end compartment formed by the baffle 37 an overflow pipe 39 is provided through which any excess of liquid in 15 the tank 10 may be discharged. At the other end of this end compartment a float 40 is positioned in a well 41 in the bottom of the tank 10. It is to be understood, however, that the use of a well is not necessary since 20 the float may be positioned in the tank itself. However, this provision of a well is deemed preferable. A flexible cable 42 is fixed at one end to the float 40 and at its other end to a pin 43 so that a vertical movement of the float 25 40 will move the pin 43 horizontally through the guide 43a, toward and from the sleeve 17. The length of the cable 42 is such that when the float 40 is at its maximum height governed by the casing 44, the locking pin 43 30 will be advanced toward the sleeve 17 a sufficient distance to obstruct the downward movement of the sleeve 17. When the float 40 is in its lowest position the pin 43 will be withdrawn sufficiently to escape the flange 35 22 in order to permit the sleeve 17 to be lowered when the tank 10 and the well 41 are empty.

What we claim is:

1. A locking device for a swing pipe adapted to receive liquid from a plurality of filling lines comprising, a sleeve telescopically positioned within the swing pipe to contact with an outlet of one of said filling lines when in its extended position, means to lower and raise said sleeve in said swing pipe, and locking means positioned to contact, in its locking position, with said sleeve to limit the retraction thereof.

2. A locking device for a swing pipe adapted to receive liquid from a plurality of filling lines comprising, a sleeve telescopically positioned within the swing pipe to contact with an outlet of one of said filling lines when in its extended position, means to lower and raise said sleeve in said swing pipe, and a locking pin positioned to contact, in its locking position, with said sleeve to limit the retraction thereof.

3. A locking device for a swing pipe adapted to receive liquid from a plurality of filling lines comprising, a sleeve telescopically positioned within the swing pipe to contact with an outlet of one of said filling lines when in its extended position, a handle adapted to engage said sleeve to lower and raise said

sleeve in said swing pipe, and locking means positioned to contact, in its locking position, with said sleeve to limit the retraction thereof.

4. A locking device for a swing pipe adapted to receive liquid from a plurality of filling lines comprising, a sleeve positioned within the swing pipe to contact with an outlet of one of said filling lines when in its extended position, means to lower and raise said sleeve in said swing pipe, and locking means positioned to contact, in its locking position, with said sleeve to limit the retraction thereof. 70

5. A locking device for a swing pipe adapted to receive liquid from a plurality of filling lines comprising a sleeve telescopically positioned within the swing pipe to contact with an outlet of one of said filling lines when in its extended position, said sleeve having a pair of spaced ribs located above said swing pipe, a pivoted handle having an end located between said ribs adapted to raise and lower said sleeve, and locking means positioned to contact, in its locking position against sleeve between said ribs to limit the retraction of said sleeve. 80

6. A locking device for a swing pipe adapted to receive liquid from a plurality of filling lines comprising a sleeve telescopically positioned within the swing pipe to contact with an outlet of one of said filling lines when in its extended position, said sleeve having a pair of spaced ribs located above said swing pipe, a pivoted handle having an end located between said ribs adapted to raise and lower said sleeve, and a locking pin positioned to contact, in its locking position against sleeve between said ribs to limit the retraction of said sleeve. 95

7. A locking device for a swing pipe adapted to receive liquid from a plurality of filling lines comprising, a sleeve telescopically positioned within the swing pipe to contact with an outlet of one of said filling lines in its extended position, said sleeve having a pair of spaced ribs located above said swing pipe, a bracket mounted on said swing pipe, a handle pivotally mounted therein and having an end positioned between said ribs adapted to lower and raise said sleeve, a locking pin positioned to contact, in its locking position, against said sleeve and between said ribs to limit the retraction of said sleeve. 105

8. A locking device for a swing pipe adapted to receive liquid from a plurality of filling lines comprising a sleeve telescopically positioned within the swing pipe, to contact with the outlet of one of said filling lines when in its extended position, a handle adapted to engage said sleeve and raise and lower it in said swing pipe, a locking pin positioned to contact in its locking position with said sleeve to limit the retraction of said sleeve. 110

9. A locking device for a swing pipe 120

adapted to receive liquid from a plurality of filling lines, comprising a sleeve telescopically positioned within the upper end of a swing pipe to surround the outlet of one of said filling lines when in its extended position and having spaced projections above the end of the swing pipe, a pivoted handle having an end adapted to contact with said spaced projections to raise and lower the sleeve, a locking pin positioned to contact in its locking position with a projection on said sleeve to limit the retraction of the sleeve and means for withdrawing said locking pin to escape the projection.

15 In testimony whereof we affix our signatures.

RICHARD J. GOLLONG.
